UNITED STATES PATENT OFFICE.

CHARLES OWENS, OF CHATTANOOGA, TENNESSEE, ASSIGNOR OF ONE-HALF TO DWIGHT PRESTON MONTAGUE, OF CHATTANOOGA, TENNESSEE.

PASTING MECHANISM FOR WRAPPING AND LABELING MACHINES.

SPECIFICATION forming part of Letters Patent No. 735,405, dated August 4, 1903.

Application filed March 15, 1902. Serial No. 98,374. (No model.)

To all whom it may concern:

Be it known that I, CHARLES OWENS, a citizen of the United States, residing at Chattanooga, Hamilton county, Tennessee, have invented certain new and useful Improvements in Pasting Mechanism for Wrapping and Labeling Machines, of which the following is a specification.

My invention relates to pasting mechanism for magazine wrapping and labeling machines.

Part of the invention is an improvement upon pasting mechanism for magazine wrapping or folding machines—such, for instance, as that disclosed in application for Letters Patent of the United States filed by me December 6, 1901, Serial No. 84,951.

In the present construction I utilize a constantly-rotating part and employ a carrier adapted to rotate when it is thrown into connection with the constantly-rotating part, said connection being effected automatically at the time and as a consequence of the feeding to the carrier of the magazine or other wrapped article which is to be pasted.

My present invention embodies the same general idea as is disclosed in the pasting mechanism of the application referred to, and the features of differences over said former construction will be referred to in the following specification and particularly pointed out in the claims.

Another part of my invention relates to means for severing labels from a web and applying them one by one to the wrapped magazines.

In the accompanying drawings, Figure 1 is a side elevation of the pasting mechanism, the left-hand portion of the figure being broken away to show the parts in rear of the outside framework and the folding, pasting, and delivery rolls being indicated diagrammatically. Fig. 2 is a view of the carrier and some of the rollers looking from the right of Fig. 1. Fig. 3 is a detail view of a switch or controlling lever and its support. Fig. 4 is a detail view of a different form of switch or controlling lever. Fig. 4^a is a detail view. Fig. 5 is a plan view of the label-pasting mechanism. Figs. 6, 7, and 8 are views of detail

parts of Fig. 5. Fig. 9 is a view of the label-strip.

In the drawings I have indicated the feeding-rolls at 8 9 and the folding and wrapping rollers at 20, 24, and 28, these being substantially the same as those in my application referred to.

68 indicates the pasting-roll, and 69 and 70 the delivery-rolls, paste being supplied to the roll 68 from a roll 68' in a tank 68^X. The 60 pasting mechanism is designed for the purpose of taking the wrapped magazine or other article as it leaves the folding-rollers 20 and 28 and carry it to the paste-roll 68, where paste is applied, and to then carry it to the 65 delivery-rolls for the discharge of the magazine with its wrapper properly folded and pasted. The carrying means in my present construction comprises a rotary drum or frame carrying a plurality of holding devices 70 for the magazines or other articles, said devices being disposed at different points about the circumference of the said drum. The drum comprises heads or end frames 3 and 4, preferably in the form of wheels having spokes 75 and loosely mounted by their hubs 3' 4' upon a central shaft 5, these heads or end frames carrying mounted therein a number of shafts 6, which are adapted to turn in their bearings in the said heads. Each of these shafts 80 carries holding means for the magazines, consisting, preferably, of two pairs of fingers *a* and *c*, held by a block *b*, fixed to the shaft 6. Fingers *c* are adapted to yield, and, as shown in Fig. 1, when the carrier is at rest 85 one pair of fingers will be opposite the bite of the rollers 20 and 28 to receive the magazines therefrom, and when the magazine is thrust into place between the fingers it will be securely held by the spring-pressure from 90 the fingers *c*. The carrier is intended to rotate step by step, and for this purpose I pivot on the outer side of the end frame or head 3 a series of pawls 7, and for simplicity of construction I utilize the extended ends of shafts 95 6 for the pivots of said pawls. In the same vertical plane with the pawls I fix upon the constantly-rotating shaft 5 a ratchet or notched wheel 10. Outside of this ratchet or notched wheel and outside also of the verti- 100

cal plane of the pawls a frame 9^x is located, this being fixed in relation to the movable pawls and the rotary ratchet or notched driving-wheel. This fixed frame has a camway 5 therein comprising a groove $9'$, formed on its inner side and extending concentrically of the center of rotation of the carrier, and a low part $9''$ of this camway is formed by cutting away the frame, as shown in Figs. 1 and 10, between the points x and y . The pawls 7 have pins $7'$, adapted to engage the camway, and thus control the position of the pawls in relation to the toothed driving-wheel. The position of the pawls is also controlled by a 15 switch-lever 2, pivoted at $2'$ to the fixed frame 9^x and having at one end a lug 13, adapted when the switch-lever is in the position shown in Fig. 1 to form practically a continuation of the supporting-surface of the camway $9'$ 20 to hold the pin with its pawl up. At the other end of this switch or controlling lever a cut-off lug or projection 14 is provided adapted when the switch is in the normal position shown in Fig. 1 to lie across the 25 camway $9'$ and form a stop for the pin on the pawl, and thus limit or arrest the rotary movement of the carrier. The toothed wheel 10 has recesses 10^x , into which the projections 7^x of the pawls fall to connect with the said 30 wheel. Supposing the parts to be in the position shown in Fig. 1 and the toothed wheel 10 in constant rotary movement, it will be seen that all the pawls will be out of engagement with the toothed wheel and the carrier 35 will be at rest, owing to a pin $7'$ on one of the pawls bearing against stop 14. As a magazine is fed into the space between the holding-arms a c its front edge will strike a bent releasing-finger d , which is connected 40 with the switch-lever, and thus the said switch-lever will be swung on its pivot $2'$. This will accomplish two things. The pawl which has been held arrested by the lug 13 of the switch-lever will be allowed to fall into the path of the teeth of the wheel 10, and at the same time 45 the stop 14 will be moved out of the path of the pin of the adjacent pawl. The carrier will now be rotated by the engagement of the released pawl with the toothed wheel 10, and this 50 engagement will continue until the pin on this pawl, riding upon the upwardly-inclined cam-surface $9''$, will be released from the toothed wheel. Before this release takes place, however, the switch or controlling lever has been 55 automatically returned by a suitable spring to the position shown in Fig. 1, with its stop 14 directly across the mouth of the camway $9'$, and as the pawl which has just engaged the toothed wheel is lifted out of engagement 60 therewith the pin on this pawl will strike the stop 14 and arrest the rotary movement of the carrier, and at the same time the next following pawl will have arrived in position, so that its pin will rest upon the block 13 ready 65 for the release of this pawl and its engagement with the toothed wheel when the next magazine is fed into the holding-arms corre-

sponding thereto. It will be seen from the above that the carrier has a step-by-step rotary movement, and at each action a set of 70 holding-arms will be presented to the bite of the rollers 20 and 28 to receive the magazine therefrom.

On the shaft 6 and outside of the drum-head 4 pinions 12 are arranged, said pinions 75 being mutilated by having a space $12'$ equal to four teeth left blank. This space is designed to engage at times with a smooth track or locking-surface of a ring 11. This ring is provided at intervals with rack-teeth 80 $12''$ and is fixed in relation to the rotary parts. I have shown three such racks located at different points on the inner edge of the ring, one set of teeth being beneath the feed-rollers 8 and 9, which feed in the blank, another set of teeth being opposite the roller 28, and another set being between the rollers 68 and 69 and 70. By this construction it will be seen that the receiving and holding fingers between which the magazines are fed 85 and also the holding-fingers at the paste-roll 68 rotate backwardly by reason of the pinions connected with these holders engaging with the teeth on the track or rim at these points, while the fingers which are below the 90 blank feed-rolls 8 and 9 are turned outwardly into position to receive the next magazine. The teeth near the roll 28 are simply for the purpose of allowing the receiving and holding fingers with the magazine held thereby 95 to clear the roll, for which purpose the pinion with the shaft 6 and the holding-arms carried thereby are rotated in the direction of the arrow, Fig. 1. The rack-teeth opposite the rolls 8 and 9 are for the purpose of turning the holding-arm inwardly, so as to pass the 100 said roller 9, and for then turning the arm outward in position for receiving the magazine. The position of the holder with the magazine in relation to the paste-roller when the carrier is at rest is shown in dotted lines in Fig. 1. It will be noticed from Fig. 1 that the holding-arms present the magazine to the pasting-roll 68, and this is done just before the carrier completes its movement. As it 105 is coming to rest the arm removes the magazine to which the paste has been applied slightly away from the paste-roller 68, because the pinion 12 engages the third section of rack $12''$ a moment before the step movement of the carrier is finished. When the carrier makes its next step, the pinion 12 will be rotated and the arms a c swung in the direction of the arrow, and as this step movement is being completed the magazine will 110 be presented to the bite of the delivery-rolls 69 and 70. In this action the holding-arms in turning sweep across the upper periphery of the roll 70, and this causes the projecting flap of the wrapper to be turned over onto 115 the paste-supplied part of the magazine, and the delivery-rolls now taking the magazine complete the folding down and pasting of 120 the flap of the wrapper.

It will be seen that the pinions 12 when not engaging the rack-teeth are locked by the segmental portion 12' engaging the plain part of the inner edge of the ring 11.

Referring now to the label-pasting mechanism, which I have arranged to coöperate with the pasting mechanism for the magazine-wrapper above referred to, it will be seen from Fig. 1 that the labels are fed in the form of a strip 15 between feed-rolls 16 and 17, and from them the label-strip is directed toward the bite of the delivery-rolls 69 and 70. Paste is supplied to the label-strip as it lies on the roll 16 by a paste-transporting roll 18. This roll has its periphery interrupted at intervals, as shown in Figs. 1 and 6 at 19, and it is arranged to take paste onto the peripheral portions 21 from the paste-roller 68, before mentioned, and it delivers it onto the label-strip at intervals. The label bearing the address is comparatively small in relation to the magazine or other article, and the width of the label-strip is indicated in Fig. 9, this being in the same proportion as the figures of the drawings representing the mechanism. The length of the label-feeding rolls as compared with the rolls for engaging the magazines is shown in Fig. 5. The paste-applying roll 18 is shorter than the label-feeding rolls 16 and 17, the purpose being to apply the paste not over the whole width of the label-strip, but, as shown in Fig. 9, to only that portion inclosed within the imaginary dotted lines indicated in said figure. This will leave a margin of one-fourth inch along each edge of the label-strip, and the paste-covered portions of the strip will be separated by an uncoated transverse portion one-half inch in width, as at 22. This spacing between the coated surfaces results from the interrupted surface of the roller 18, before mentioned. It will be understood that the label-strip has been previously supplied with the desired addresses spaced apart properly and uniformly, and the diameter of the roller 18 is such that the paste will be applied to the label-strip at intervals corresponding to the positions of the printed addresses, but on the reverse side of the paper therefrom. The feed-roller 17 has an interrupted periphery, only its end portions or rims 23 presenting continuous cylindrical surfaces. These continuous surfaces are adapted to bear on the plain uncoated margins of the label, and for this purpose they are made about one-fourth inch or less in width. By engaging with the plain uncoated portions accuracy of feed is insured, as these margins are not puckered up, which puckering affects the accuracy of the feed, and the surface of the feed-roller is kept free from paste or accumulations thereof.

The detail construction of the feed-roller 17 is illustrated in Fig. 7, from which it will be seen that it is provided with three spaces 24, which overlie the label-strip when the paste-coated portions are passing through the feed-

rolls. At other times the knives 25, carried by the feed-rollers, engage the label-strip centrally of the intermediate plain or uncoated portions of the strip and perforate or partially sever the same, so that the labels are partially severed from the strip, the companion feed-roller 16 being provided with grooves at 24' to act as the female part of the cutter or perforator. This roller has its periphery intact except where the grooves occur, and it forms the support upon which the label-strip bears and between which and the rims or bearing portions of the feed-roll 17 the label-strip is gripped to be fed positively and accurately to the delivery-rollers.

The train of rollers is driven from the rotary magazine-carrier at proper intervals by means of rack-teeth 26, formed on the rotating heads or frames 3 and 4, meshing with a pinion 27, there being a set of these rack-teeth in advance of each pair of magazine-holding arms, so that as a magazine after receiving paste is being carried to be presented to the delivery-rolls the said rack-teeth 26 will rotate the pinion, and through gearing 29 30 31 on the shafts of the rolls 17, 16, and 18, respectively, these rolls will be turned in the proper direction to present the label properly supplied with paste and almost severed from the strip to the rollers 69 70, and when the magazine is brought to the bite of these rollers the added thickness or the pressure of the magazine on the label will cause it to be torn from the strip and be applied to the magazine. Another advantage appears here, resulting from having a clean margin around the paste-coated surface, in that there is no liability of the paste being squeezed beyond the edge of the label and getting upon the surface of the rollers.

I do not wish to limit myself strictly to the use in one machine of the wrapper-paster and the label-paster.

In Fig. 4 I show a modified form of the switch or controlling-lever, in which the lever is formed of a single arm. This has the supporting-surface 13' and also the stop 14', combined therewith. These parts are thus arranged to act on the same pin 7' of one of the pawls.

The knives that sever the labels make a clean cut excepting at the margins, where the strip is perforated to be readily torn. The line of cut is indicated in Fig. 9.

I claim as my invention—

1. In combination, a carrier for magazines and the like comprising a step-by-step rotary part and means for giving the same step-by-step rotary movement in one direction, said means being rendered effective to rotate the carrier by the feeding of the magazine into said carrier, substantially as described.

2. In combination, a rotary carrier, a plurality of holding devices thereon for the magazines and means for giving said carrier a step-by-step rotary movement, said means being

controlled automatically by the feeding of the magazines into engagement with the carrier, substantially as described.

3. In combination, a constantly-rotating part, a carrier adapted to rotate step by step in one direction and means for throwing the same automatically into and out of connection with the constantly-rotating part, said automatic means being controlled by the feeding of the magazines into their position on the carrier to be carried thereby, substantially as described.

4. In combination, a carrier, holders supported thereon to have a swinging movement, a paste-container, discharge-rolls and means for swinging said holders automatically in relation to the paste-container and discharge-rolls, substantially as described.

5. In combination with a step-by-step rotary carrier, a series of holding means radiating therefrom and pivotally connected with the carrier, a paste-roll, discharging-rollers and means for automatically swinging said holding means about their pivots, substantially as described.

6. In combination, a step-by-step rotary drum or carrier, a series of pawls thereon, a toothed wheel constantly rotating and arranged to be engaged by the pawls, a camway for controlling the position of the pawls and a controlling-lever with means for operating the same automatically as the magazines are fed into the machine, said lever controlling the position of the pawls in relation to the camway, substantially as described.

7. In combination with a movable carrier, means for driving the same, a pawl, a camway for controlling the position of the pawl in relation to the driving means and a switch controlled by feeding in of a magazine, said switch controlling the position of the pawl in relation to the camway, substantially as described.

8. In combination, a rotary carrier, a constantly-rotating driving member, a pawl for connecting the two, a camway for controlling the position of the pawl in relation to the driving member and a switch and stop device, said switch serving to control the position of the pawl in relation to the camway and to stop said pawl when a one-step movement of the carrier has been completed, substantially as described.

9. In combination with the rotary carrier, a pawl, a constantly-rotating toothed wheel to be engaged by the pawl, a camway to control the position of the pawl and a switch-lever pivoted intermediate of its length to control the position of the pawl in relation to the camway, said switch-lever at one end having a supporting-lug for the pawl and having at its other end a stop for said pawl, substantially as described.

10. In combination, a rotary carrier, a series of arms pivotally connected therewith, and means for controlling the position of said arms comprising a rim having teeth at inter-

vals and pinions on the pivots of the arms having blank spaces to engage plain portions of the rim, the teeth of the pinion being adapted to engage the teeth on the rim, substantially as described.

11. In combination, a carrier, holding means for the magazine movably connected therewith, a roll in the path of the outer end of the magazine and means for throwing the said holding means into different positions to pass the said roll, substantially as described.

12. In combination mechanism for pasting the wrapper onto a magazine or the like, said mechanism including a pair of delivery-rollers, a label-pasting mechanism comprising means for applying paste to the label-strip, means for partially severing the labels from the said strip and for directing the same to the discharge-rollers whereby the added thickness of the magazine in being discharged will separate the labels from the label-strip and press the label upon the magazine or wrapper, substantially as described.

13. In combination means for pasting a wrapper containing a magazine or the like, means for discharging the wrapped magazine comprising a pair of rolls between which the wrapped magazine passes and means for feeding the labels thereto to be applied to the magazine or wrapper by the pressure of said rolls as the magazine is being discharged, substantially as described.

14. In combination with mechanism for pasting a wrapper containing a magazine including a pair of discharge-rollers and means for feeding the labels to the discharge-roller to be applied to the magazine or wrapper by the action of said discharge-roller.

15. In combination with a rotary carrier for the magazines, means for giving the same a step-by-step movement, means for applying labels to the magazines and means for operating the said label-applying means intermittently from the rotary carrier, substantially as described.

16. In combination with rollers through which the magazines or the like are passed, means for applying paste to a sheet leaving its margins free, means for partially severing said sheet and means for feeding the same by its margins to the rollers to be attached to the magazine or the like, substantially as described.

17. In combination, a pair of discharge-rollers for the magazine, means for presenting the magazine thereto and means for directing the labels to the discharge-rollers to be applied to the magazines as they are passing through the discharge-rollers, substantially as described.

18. In combination, a pair of discharge-rollers for the magazine, means for presenting the magazine thereto and means for directing the labels to the discharge-rollers to be applied to the magazines as they are passing through the discharge-rollers, said labels be-

ing severed from the label-strip by the contact of and pressure resulting from the magazine, substantially as described.

19. In combination, means for effecting the discharge of a magazine, and means for directing a label-strip thereto, the said labels being severed from the strip and applied to the magazine by the added thickness of the magazine in passing through the discharge means, substantially as described.

20. In combination, a carrier having a movable holder for the magazine, means for acting on the magazine, said means being located in and obstructing the path of the magazine

as moved by the carrier, and means for moving the holder in relation to the carrier in order to pass the said obstructions, substantially as described.

21. In combination, a movable carrier with means for moving the same intermittently, a paste-container and a holder on the carrier with means for operating said holder to lift the magazine from the paste-container just before the carrier comes to rest, substantially as described.

22. In combination, a movable carrier, a paste-roller, a holder for the magazine, a pair of delivery-rollers and means for giving the

holder a movement on the carrier, said movement being in a reverse direction opposite the delivery-rolls to cause the flap to be folded down, substantially as described.

23. In combination, a carrier having rotary step-by-step movement in one direction, a holder for the magazine carried thereby, means for applying paste to the magazine held by the said holder and in the forward movement of the carrier and holder, means for giving the holder a reverse movement in relation to the carrier with means for folding down the flap in said reverse movement, substantially as described.

24. In combination, a carrier, a holder for the magazine pivoted thereto, means for applying paste to the magazine, means for folding down the flap of the wrapper and means for swinging the holder in a direction opposite to that of the carrier to cause the magazine to contact with the flap-folding means, substantially as described.

In testimony whereof I affix my signature in presence of two witnesses.

CHARLES OWENS.

Witnesses:

THEO. L. MONTAGUE,
JOHN H. CANTRELL.
